CLAIM

The ornamental design for an injection device, as shown and described.

DESCRIPTION

FIG. 1 is a top perspective view of an injection device, showing the new design.

FIG. 2 is a front elevational view of the injection device.

FIG. 3 is a rear elevational view of the injection device.

FIG. 4 is a right side elevational view of the injection device.

FIG. 5 is a left side elevational view of the injection device.

FIG. 6 is a top view of the injection device; and,

FIG. 7 is a bottom view of the injection device.

Portions of the injection device shown in broken lines form no part of the design as claimed.
